Fig. 3.

FIG. 1 is a plan view of the pizza embodying my new design and showing a pizza in the form of a dog's head with cheese strips representing hair, pepperoni slices representing ears, and olives representing the eyes and nose, with all of the foregoing being placed on a dough crust;

FIG. 2 is an elevational view looking at FIG. 1 from the bottom of the page;

FIG. 3 is an elevational view looking at FIG. 1 from the top of the page;

FIG. 4 is an elevational view taken from the right of FIG. 1; and

FIG. 5 is an elevational view taken from the left of FIG. 1.

The bottom of the pizza is substantially plain and unornamented.

I claim:

The ornamental design for a pizza, substantially as shown and described.
